UNITED STATES PATENT OFFICE

2,398,914

WINDOW VENTILATOR

William V. Barrowclough, Cadillac, Mich., assignor to Insulated Windows, Inc., a corporation of Michigan

Application May 15, 1944, Serial No. 535,727

3 Claims. (Cl. 98—97)

My invention relates to a new and useful improvement in a window ventilator adapted for mounting in windows of various types, including storm windows.

It is an object of the present invention to provide a ventilator of this class formed from a single piece of fabric and having louvers or deflecting plates extending longitudinally thereof and normally inclined to the horizontal, the spaces between which may communicate with transversely disposed outlet openings.

It is another object of the present invention to provide a ventilator of this class having the longitudinally extending louvers communicating with the vent openings and connected together and to the main body at the space between the openings.

Another object of the invention is the provision of a ventilator of this class which is simple in structure, economical of manufacture, durable and easily and quickly installed.

Other objects will appear hereinafter.

It is recognized that various changes and modifications may be made from the detail of structure illustrated and it is intended that such shall be encompassed within the scope of the claims which form a part hereof.

Forming a part of this specification is a drawing in which,

Fig. 1 is a front elevational view of a window showing the invention applied;

Fig. 2 is a sectional view taken on line 2—2 of Fig. 1, slightly enlarged;

Fig. 3 is a rear elevational view of the invention;

Fig. 4 is a sectional view taken on line 4—4 of Fig. 3, slightly enlarged;

Fig. 5 is a sectional view taken on line 5—5 of Fig. 4;

Fig. 6 is a fragmentary front elevational view with parts removed;

Fig. 7 is a sectional view, slightly enlarged, taken on line 7—7 of Fig. 3.

In the drawing, I have shown the invention applied to a window, embodying the side rails 8 and 9 and the end rail 10. The ventilator plate 11 is provided on its upper edge with a tongue 11a interlocking with a tongue 72 on the lower rail 73. Formed in the front or outer face of the plate 11 are a series of spaced apart slots 12 which extend longitudinally of the plate 11 and are inclined, as clearly shown in Figs. 4 and 7. By forming these slots 12 in spaced relation, the louver or shutter-forming members 14 are thus formed. The inner face of the plate 11 is cut out

5 to provide a channel 15 in which is slidably mounted a closure plate 18 having the knob 18a mounted thereon. Fixedly mounted in the channel 15 at opposite ends, to serve as abutments for the slidable closure 18, are the closure plates 16 and 17. Extending transversely of the plate 11 are formed, on the inner face of the channel 15, the transverse openings 20 which are cut inwardly deep enough to communicate with the spaces 12. Formed in the slidable closure 18 are openings 19 corresponding in size and spacing to the openings 20. The construction is such that when the slidable plate 18 is slid so that its openings 19 register with the openings 20, air may pass 10 through the openings 19 and 20 and through the spaces or channels 12 which lie between the louvers or shutters 14. When the slidable closure 18 is moved so that its openings 19 do not register with the openings 20, the ventilator may be 15 said to be closed, as shown in Fig. 5. In Fig. 6, I have illustrated a front elevational view with the slidable closure plate 18 removed so that the formation of the openings 20 more clearly appears. It will be noted that there is a rib 13 between each of the openings 20 and, as shown 20 clearly in Fig. 7, this rib 13 is integral with the louver or shutter-forming member 14. Consequently, these members 14 are free from connection at the openings 20, as clearly appears in Fig. 4, but are not disconnected at the space between the openings 20. These members 14 are formed of quite thin material and if they were to be stretched over a wide expanse to cover a wide window opening, they would have a tendency to sag 25 if they were loose throughout their length. With this method of formation, however, they are connected integrally with the member 11 between each opening 20 and a strong, durable structure is thus provided.

40 This method of construction also lends to an economical manufacture of a ventilator of this type. A routering operation is resorted to in order to form this channel 15. The spaces 20 and the louvers 14 are formed by a routering operation. The openings 20 are then routered from the face 15 extending inwardly until they meet the members 14 so that when looking at the openings 20 from the front with the slide 18 removed, the shutters 14 are visible, as clearly appears in Fig. 6 and Fig. 4. The method of mounting and 45 securing the slidable plate 18 in position is also a simple and effective one requiring a minimum amount of labor operations.

50 What I claim as new is:

1. A window ventilator of the class described,

comprising: an elongated plate having a plurality of horizontally directed vertically spaced apart slots formed inwardly from one face of said plate and extending inwardly of said plate a distance less than the thickness of said plate to provide a plurality of spaced apart horizontally directed louvers integral with said plate, there being a horizontally directed channel formed in the opposite face of said plate, extending from end to end thereof and being of less depth than the thickness of said plate, said plate having a plurality of horizontally spaced apart vertically directed narrow slots formed inwardly thereof from the base of said channel a distance less than the thickness of said plate and inwardly of said plate a sufficient distance to communicate with said slots between said louvers; a slide plate slidably mounted in said channel and having a plurality of spaced apart vertical slots formed therein and slidable into and out of registration with said vertically directed slots in said plate; and means at opposite ends of said channel for limiting slid-
able movement of said slide plate in said channel.

5 2. A window ventilator of the class described, comprising: an elongated plate having a plurality of horizontally directed vertically spaced apart slots formed inwardly from one face of said plate and extending inwardly of said plate a distance less than the thickness of said plate to provide a plurality of spaced apart horizontally directed louvers integral with said plate, there being a horizontally directed channel formed in the opposite face of said plate, extending from end to end thereof and being of less depth than the thickness of said plate, said plate having a plurality of horizontally spaced apart vertically directed narrow slots formed inwardly thereof from the base of said channel a distance less than the thickness of said plate and inwardly of said plate a sufficient distance to communicate with said slots between said louvers; a slide plate slidably mounted in said channel and having a plurality of spaced apart vertical slots formed therein and slidable into and out of registration with said vertically directed slots in said plate.

WILLIAM V. BARROWCLOUGH.
